AUTOMATIC FEED WATER CONTROL

Application filed May 31, 1930. Serial No. 458,255.

My invention relates to feed water controls for use in controlling the feeding of water to boilers more particularly for use in controlling the feeding of water to the boilers of locomotives and the like, and it consists in the combinations, arrangements and constructions herein shown and described.

In some locomotives the feed water is heated by the exhaust steam coming from the cylinders which makes it necessary to inject the water into the boiler only at the time the engine is being worked and consequently supplying exhaust steam. Since the locomotive works intermittently and the supply of the exhaust steam varies from zero to a maximum, at times within short periods, the feed water control must be operated to vary the supply of feed water accordingly to assure proper feeding of the water. This means that the pump which supplies water to the heater and the boiler cannot be operated by merely starting and stopping the same but must be made to operate slowly and rapidly in accordance with the variations in the amount of exhaust steam supplied. It is therefore a primary purpose of my invention to provide an automatic feed water control for particular use in locomotives which will automatically vary the supply of water to the boiler in accordance with the supply of exhaust steam, occasioned by the use of the steam in the boiler, thereby eliminating the necessity of any manual handling of the supply of water in the locomotive boiler from one terminal to another.

A further object of my invention is to provide an automatic feed water control for particular use in locomotives which will give a signal to an operator if for any reason the feed water control is not operating properly, which faulty operation may be occasioned by leakage in the control tank of the feed water heater and associated parts or because of a leaky packing ring, delivery pipe, etc. or for some other reason.

A further object of my invention is to provide a device of the type described which is adapted to carry out its functions on a locomotive or in any other heating system

whether the water be preheated by an injector or by any other conventional means.

A further object of my invention is to provide a device of the type described which by means of its particular arrangement is adapted to perform its functions properly whether the locomotive is running on the level, up hill, or down hill, around curves, or otherwise carrying out its natural functions.

A still further object of my invention is to provide a device of the type described which has few parts, is simple to manufacture and does not get out of order easily.

Other objects and advantages will appear as the specification proceeds and the invention will be more particularly defined in the appended claims.

My invention is illustrated in the accompanying drawings forming a part of this application in which:

Figure 1 is a schematic representation of the invention;

Figure 2 is a side elevation of the mechanical portion of the invention;

Figure 3 is an end elevational view of the mechanical portion of the device; and

Figure 4 is a sectional view on line 4-4 of Figure 2.

In carrying out my invention, I have described the device as installed upon an ordinary locomotive having a feed water pump (not shown). In Figure 1, I show a steam pipe 1 including a steam throttle 2 which may be of any suitable or conventional construction and which is actuated by the bar 3. It is by means of this steam throttle valve 2 that I control the flow of the water into the boiler in accordance with the amount of steam exhausted during the operation of the locomotive with a consequent decrease of the supply of water within the boiler.

For operating the valve 2 to vary the amount of water fed into the boiler in accordance with the extent of the operation of the locomotive, I utilize a tank 4 which is connected with the boiler by a suitable conduit 4^a to provide a water level in this tank 4 which will vary in accordance with

the supply of water in the boiler. In order that the water level in said tank will not be varied to any great extent during the up-hill and down-hill movements of the engine 5 the same is positioned at the longitudinal center thereof.

The pipe 4a connecting this tank to the boiler 4c is positioned preferably at the transverse center of both the tank and the 10 boiler, so that the water level in the tank will not be affected when the locomotive rounds curves or "banks" for other reasons. A suitable pipe 4b connects the space above the water level in this tank with the steam 15 above the boiler level in the boiler, thereby equalizing the pressure throughout the fluids.

To the tank 4 at 5 is connected a conductor which communicates with terminal 6 of 20 a generator 7 for cooperation through the body of water in the tank 4 with a series of contacts 8, 9, 10 and 11 which may consist of any desired number to perform various switching operations to control the 25 action of the valve 2 in accordance with the water level in the tank. It will be noted that these contacts 8, 9, 10 and 11 are positioned at different levels relative to the body of water in the tank. This arrangement is provided for a purpose that will 30 soon appear.

The contacts 8, 9, 10 and 11 are connected as appears most clearly in Figure 1 to a corresponding series of double pole pole-changing relays 12, 13, 14 and 15 having armatures 16 and 17, 18 and 19, 20 and 21, and 22 and 23, respectively, which perform the pole-changing switching operations between contacts 24 and 25 and 26 and 27; 28 and 29, 30 and 31; 32 and 33, 34 and 35; and 36 and 37, 38 and 39, respectively. The circuit is completed from the relays 12, 13, 14 and 15 by means of the line 40 connected to said relays and to the terminal 41 of generator 7 through line 42. As can be easily understood energization of the circuit, due to the contact of water with any of the contacts 8, 9, 10 and 11, will elevate the armatures associated with the respective relays controlled by said contacts, thereby reversing the poles in the circuits controlled by the contacts 24 to 39 inclusive, by means of the armatures of the relays 12 to 15 inclusive. 45 The armatures 16 to 23, inclusive, are energized from the generator by means that will later be described.

The contacts 8, 9, 10 and 11 are provided with cylindrical shields 43 to 46 inclusive, 60 as shown most clearly in Figure 2. These shields have small perforations therein which permit the water to flow into connection with the contacts when the shields and contacts are below the water level, but prevent energization of said contacts by the

splashing of water thereon during the movements of the locomotive.

For controlling the movements of the motor 47 which actuates the throttle valve 2 70 controlling the supply of water furnished to the boiler by the feed water pump so that said motor will operate to a greater or lesser extent in accordance with the supply of water in the boiler and also the tank 4 I utilize a selector switch, generally indicated at 48, which may be of any suitable construction adapted to perform the desired functions, but which is shown as comprising a cylindrical drum 49 mounted for rotation in a frame 50 and having a plurality 75 of contacts 51 to 62 inclusive thereon. The number of contacts utilized will vary accordingly as a greater or smaller number of associated pole-changing relays comprising the armatures 16 to 23 are used. 80

It will be noted that these contacts 51 to 62 inclusive, occur in pairs and that they are placed on said cylindrical member 49 so that no set of contacts, with the exception of contacts 61 and 62, are peripherally coincident with any other set of contacts. This arrangement is adopted for reasons that are readily apparent. 90

It will be seen that the contacts 51 and 52 are connected to the lower poles 24 and 95 25 of the switch controlled by relay 12 while the next adjacent pair of contacts 53 and 54 are connected to the upper pole 26 and 27 of the switch controlled by relay 12 and that these contacts 53 and 54 are 100 connected to their associated contacts 26 and 27 in a reverse fashion to the connection between contacts 51 and 52 and their associated contacts 24 and 25. It will further be noted that contacts 53 and 54 are also 105 connected to the lower contacts 28 and 29 of the switch controlled by relay 13 in the same order that contacts 51 and 52 are connected to contacts 24 and 25, while the contacts 55 and 56 are connected to the upper 110 contacts 30 and 31 of the switch controlled by relay 13 in a reverse fashion or in the same order as the interconnection between contacts 53 and 54 and contacts 26 and 27. This arrangement is continued throughout 115 the entire system and performs the reversing operation of the motor.

For association with the contacts 51 to 62 inclusive to complete the circuit there-through I provide the series of stationarily 120 positioned contacts 63 to 74, inclusive, which are in number equal to the corresponding series of contacts 51 to 62. It will be noted that the alternates of these contacts 63 to 74 inclusive, are connected to the lines 75 and 76 which I call the motor reversing or motor starting leads. These lines are connected to the field of the motor which in the embodiment shown is a motor operated by direct current. A sole- 125

noid 77 to control the armature 78 of a circuit breaker 79 is positioned in line 75 to cut out the motor upon deenergization of the lines 75 and 76. This is accomplished by the release of the armature 78 by the solenoid 77 upon said deenergization and the consequent breaking of a circuit through motor leads 80 and 81 which connect to the armature (not shown) of the motor 47. These motor leads 80 and 81 are energized and comprised in the circuit of the generator 7 as readily appears in Figure 1.

For actuating the throttle valve 2 from the motor 47 as well as for synchronizing the movements of the selector switch 48 with the movements of said motor and the extent of operation of the throttle valve 2, I provide a system of gearing, generally indicated at 82 which may consist of ordinary gears, belts, pulleys or any other suitable arrangement but which is shown as comprising a pinion 83 positioned on the shaft 84 of the motor 47 and adapted for rotating a gear 85, which rotates a shaft 86 having positioned thereon a screw 87 and worm 88 for controlling the movements of the valve 2 and the selector switch 48 respectively.

The screw 87 cooperates with a nut 89 which is swivelly connected by the means shown at 90 to a link 91 secured by means of a link 93 to a bracket 92 which may be fixed by any suitable means but which is shown as fixed to the pipe 1. This link 91 is pivoted to the valve actuating rod 3 as appears at 94.

The worm 88 is geared to the drum 49 of the selector switch 48 for rotation thereof by means of a worm wheel 95 integral with the horizontally positioned shaft 96 which mounts for rotation therewith another worm 97 for rotation of the worm wheel 98 which rotates the drum 49.

For starting and stopping the feed-water pump control in synchronism with the open and shut positions of the throttle, which controls the operation of the locomotive with consequent control of the exhaust of the

steam resulting from said operation I provide a double contact switch, generally indicated at 99, adapted for operation by a throttle 100 of a locomotive. This switch 99 comprises a resilient switching member 101 having the switching arms 102 and 103 included in the circuit of generator 7 by means of wires 104 and 105, respectively. This switching member 101 is adapted to connect the generator 1 to the armatures 16 to 23 in-

cluding the contacts 106 and 107 operating through lines 108 and 109, respectively, in one of the operative positions while in the other operative position the switch member 101 is adapted to connect the generator 7 to the lines 110 and 111 by means of contacts 112 and 113, respectively. When the throttle lever 114 is in the position as shown in Fig. 1 the switch member 101 is in contact with the switch contacts 106 and 107 to energize the lines 108 and 109. When the throttle lever 114 is moved to a position opposite that shown in Figure 1, the switch member 101 breaks the connection between the generator and contacts 106 and 107 and energizes lines 110 and 111 by means of contacts 112 and 113 respectively. As will be later described this operation reverses the direction of rotation of the motor to move the same to a stop position to close the valve throttle 2.

For sounding an alarm or signal to the operator of the feed water heater controlled by my feed water control means upon the failure of a proper supply of water to be maintained in the feed water heater and associated parts for a successful operation of my control, I provide the means generally indicated at 115. This means consists of a bell 116^a or any other suitable or desired signal which may be positioned in the cab of a locomotive if my device is used on a locomotive or at some other appropriate place if the same is desired by the operator. This bell or other signal is operated by power taken from the lines 116 and 42 by means of the connection 117^a running from one of the terminals 118 of said signal to line 42, as indicated at 119 and a connection 120 running from the other terminal 121 of the bell or other signal 116^a through a relay 122 and through the line 117 by the connection indicated at 123. The relay 122 is powered from the lines 42 and 116 by means of a cut-in on line 117^a, as indicated at 124 and by means of a contact 125 positioned in the water of the tank 4 through said water in tank 4 through line 117 to line 116. The relay, it is to be observed, is normally in open or inoperative position breaking the connection between the power source and the signal.

A main switch 128 in the circuit of the generator permits the same to be cut out when the device is not in use.

The circuits comprised in the apparatus are as follows: The double-pole pole-changing relay circuit, the motor-reversing circuit, the motor-stopping circuit, the motor-power circuit, and the signal circuit.

The double-pole pole-changing relay circuit runs from terminal 6 of generator 7 through switch 128, line 116, line 117, terminal 5 through the water to contacts 8, 9, 10 and 11 through the relays 12, 13, 14 and 15, respectively, the line 40, line 42, terminal 41, and generator 7.

The motor-reversing circuit comprises the contact 6 of generator 7, switch 128, line 116, line 105, switch arm 103, contact 106, line 108, armatures 17, 19, 21 and 23, con-

- 6 tacts 53, 55, 57 and 59, associated contacts
65, 67, 69 and 71, respectively, line 76, motor
47, solenoid of the circuit breaker 77, line
75, contacts 66, 68, 70 and 72 and associated
contacts 54, 56, 58 and 60, respectively,
contacts 26, 30, 34 and 38, associated
armatures 16, 18, 20 and 22, respectively,
line 109, contact 107, switch arm 102, line
104, line 42, terminal 41, and generator 7.
- 10 The current in this circuit of course is re-
versed at the double-pole pole-changing re-
lays 12 to 15 when the water is below the
contacts 8 to 11.

15 The motor stopping circuit comprises
generator 7, terminal 6, switch 128, line 116,
line 105, switch arm 103, contact 113, line
111, selector contact 61, associated contact
73, line 76, motor 47, line 75, solenoid 77
of the circuit breaker 79, contact 74, contact
20 62, line 110, contact 112, arm 102, switch
101, line 42, switch 128, terminal 41 and gen-
erator 7.

25 The motor power circuit comprises gen-
erator 7, terminal 6, line 116, switch 128,
motor armature lead 81, motor 47, motor ar-
mature lead 80, arm 78 of circuit breaker
79, line 42, terminal 41 and generator 7.

30 The signal circuit comprises generator 7,
connection 41, switch 128, connection 117^a,
signalling device 116^a, connection 120, relay
contactor arm 122, connection 126, wire 117,
line 116, switch 128, terminal 6 and gen-
erator 7. The relay circuit of the signal in-
cludes the circuit of the generator to line
35 117^a as heretofore set forth, a cut-in 124, the
coil of the solenoid of the relay 122, con-
nection 127, contact 125, water in tank 4,
tank 4, line 117, line 116, switch 128, and
generator 7.

40 From the foregoing description, the use
and operation of my device is easily under-
stood. The apparatus is set up as hereto-
fore described, and the main switch 128 is
45 thrown in contact for energization of the
various circuits.

50 When the water in the boiler is at a suffi-
cient height to maintain the water level in
tank 4 above the contacts 8 to 11, inclusive,
and the throttle is in opened position as
55 shown in Figure 1, the relays 12 to 15 in-
clusive are energized through the double-
pole pole-changing relay circuit. This po-
sitions the armatures 16 to 23 of the relays
60 12 to 15 inclusive of the motor-reversing
circuit in the upper position as shown which
would tend to send the current through the
contacts 53 to 60 inclusive. The current
fails to flow through said contacts however
65 for they are not in engagement with their
associated contacts 65 to 72 inclusive. In
this position of the device the motor is in a
closed position and at a stand still due to the
lack of energization of the motor reversing
70 and operating circuit. It will be noted
65 that in this position the contacts 51 and 52

are the only ones in engagement with their
associated contacts such as the contacts 63
and 64. No energization of this circuit takes
place however through these contacts be-
cause of the break in the circuit at termi-
nals 24 and 25 due to the elevation of arma-
tures 16 and 17.

75 When the water level in the boiler falls
due to the usage of steam from said boiler
and it is desired to utilize the steam from
the exhaust for the feed-water pump to heat
an additional supply of water for the boiler,
the water level in tank 4 will fall until it is
between contacts 8 and 9. This deenergizes
relay 12, leaving the double pole, pole-
changing relay circuit complete through re-
lays 13, 14 and 15 and through associated
contacts 9 to 11, respectively. At this stage
the armatures 16 and 17 will drop down
80 to engage contacts 24 and 25 thus passing
current to contacts 51 and 52 on the selector
switch. The circuit is then completed
through the motor by means of contacts 63
and 64 respectively, and their associated
lines 76 and 75 with the current first flow-
ing along line 75. When the current flows
85 in this direction in line 75 it energizes the
field of the motor 47 reversely from the en-
ergization when the current flows first along
line 76 to cause rotation of said motor in a
90 valve opening position. Of course when
the solenoid 77 in line 75 is energized the
motor-power circuit is energized to make
the motor operate.

95 This movement of the valve throttle to
100 partially opened position by means of the
actuation of the motor 47 also causes rota-
tion of the drum 49 of the selector switch 48
in synchronism with the movement of the
valve. This operation moves contacts 51 and
52 out of engagement with their associated
105 contacts 63 and 64, respectively and brings
the contacts 53 and 54 on the selector drum
into contact with their associated stationary
contacts 65 and 66, respectively. At this
110 point the motor stops because the lines 75
and 76 are deenergized. No electricity is
transmitted thereto by the contacts 55 to 60
because they are not in engagement with
115 their associated contacts 67 to 72; no elec-
tricity is sent along the lines 75 and 76 by
means of contacts 53 and 54 because of the
breach occurring at the contacts 28 and 29
due to elevation of arms 18 and 19, and be-
cause the arms 16 and 17 are in the lowered
120 position due to the water level being be-
tween contacts 8 and 9, and no electrical
energy is transmitted to lines 75 to 76 by
way of contacts 51 and 52 though the cir-
cuit is not broken at the relay because con-
125 tact 51 and 52 have ridden out of engage-
ment with their associated contacts 63 and
64, respectively.

130 If the engineer continues to use steam
faster than the same is supplied by the water

from the feed-water pump when the throttle valve 2 is opened, the level in the tank 4 will drop between contacts 9 and 10 whereupon the operation just described in regard to contacts 8 and 9 will be repeated, thus actuating the motor to a position of greater partial opening of the throttle valve 2.

Upon the lowering of the water level in tank 4 below the contact 11, the motor will remain stationary in the full open throttle valve position.

If the water level in tank 4 continues to be lowered, due to improper operation of the feed water heater control with a consequent lack of an additional supply of water to the boiler, or due to leakage from tank 4 or associated parts of the boiler or for other reasons until it passes beyond the contact 125, the relay 122 will become deenergized because of the breach in the circuit existing between contact 125 and the water in tank 4, thereby closing the alarm circuit through said relay to sound the alarm 116^a indicating to the operator that the system is out of order, thus enabling said operator to remedy the trouble for subsequent operation of the control. Of course, when the water in the tank rises to cover said contact 125, the alarm will cease to be given.

When the water level in this tank 4 rises to engage contact 11, the armatures 22 and 23 of relay 15 will be elevated as shown to send the current of the motor reversing circuit through contacts 38 and 39, contacts 60 and 59 and their associated contacts 72 and 71 with the current flowing first along the line 76 to the motor and from the motor along line 75, this being the reverse of the direction of current when the armatures 23 and 22 are in the lowered position, in which case current flows through line 75 to the motor and from the motor by line 76, thereby reversing the direction of flow of the current through the field of the D. C. motor, reversing said motor. This reversal of the motor operates the valve 2 to a valve closing position and also reverses the direction of rotation of the drum 49. Upon further rising of the water level, the circuits comprising the remaining relays 14, 13 and 12 are similarly energized bringing about a reversal of the motor and moving the valve 2 to a more nearly closed position upon energization of each of said relays, until when the water reaches the level shown in Figure 1 the motor has been moved to full valve closing position.

If the throttle is moved to the closed position by the engineer when the selector is in any position in which the contacts below the contacts 51 and 52 on the drum are in engagement with their associated stationary contacts, the motor-stopping circuit will be energized by means of the switch 99, through arms 102 and 103 of the switch member, con-

tacts 112 and 113, lines 110 and 111, contacts 62 and 61 and their associated contacts 74 and 73, lines 76 and 75 with the current flowing through line 76 to the motor and through line 75 from the motor thereby operating said motor to a valve-closing position. This operation continues until the motor operates the valve to fully closed position because of the elongated peripheral extent of contacts 61 and 62.

It is thus seen that I have provided a feed water control which is particularly adapted for use on locomotives wherein an automatic control is desired for feeding the water in proportion to the supply of steam occasioned by the use to which the heating system is put.

It may also be easily seen that my device is adapted for efficient operation in all of the usual positions and under all the ordinary conditions of operation of locomotives.

I claim:

1. In a feed water control system, a water reservoir, a steam boiler connected therewith, means for controlling the flow of steam from said boiler, a motor for operating said controlling means and adapted for reversal upon reversal of electric current flowing therethrough, a selector switch for controlling the movements of said motor and means operative through said selector switch for reversing the direction of movement of said motor comprising a series of double pole changing relays adapted for energization and de-energization in synchronism with the exhaust of liquid from the boiler and change of liquid level in said water reservoir.

2. In a feed water control system, a water reservoir, a steam boiler connected therewith, means for controlling the flow of steam from said boiler, an electric means for operating said controlling means to the open and shut positions, a selector switch for controlling the movements of said electric means, means operative through said selector switch for energizing and de-energizing said switch in synchronism with the exhaust of liquid from the boiler, and means operative through said selector switch for positioning said switch to operate said motor to move said controlling means to the closed position when the exhaust of steam from the boiler is arrested.

3. In a feed water control system, a water reservoir, a steam boiler connected therewith, electrically operated means for controlling the flow of steam from said boiler, a series of relays adapted for energization of circuits controlling the operation of said electrically operated steam controlling means to various stages of its open and shut positions, and means for the energization of said relays to move said electrically operated steam controlling means through the various

stages of operation in accordance with the water level in said reservoir.

4. In a feed water control system, electrically operated means for controlling the flow of steam from said boiler, a series of relays adapted for energization of circuits controlling the operation of said electrically operated steam controlling means to various stages of its open and shut positions, and means for the energization of said relays to move said electrically operated steam controlling means through the various stages of operation, comprising an auxiliary water tank connected with the boiler to maintain a water level variable in accordance with the water level in said boiler, a contact with a source of electrical current supply in its circuit positioned in said water, and a series of contacts connected to said relays for the operation thereof and positioned at different levels in said auxiliary tank for energization and de-energization upon contact with the water in said tank.

5. In a feed water control system, electrically operated means for controlling the flow of steam from said boiler, a series of relays adapted for the energization of circuits controlling the operation of said electrically operated steam controlling means to various stages of its open and shut positions, means for the energization of said relays to move said electrically operated steam controlling means through various stages of operation, comprising an auxiliary water tank connected with the boiler to maintain a water level variable in accordance with the water level in said boiler, a contact with a source of electrical current supply in its circuit positioned in said water, and a series of contacts connected to said relays for the operation thereof and positioned at different levels in said auxiliary tank for energization and de-energization upon contact with the water in said tank, said contacts having means positioned thereabout for shielding said contacts against energization due to irregular movements of the water.

6. In a feed water control system, electrically operated means for controlling the flow of steam from said boiler, a series of relays adapted for the energization of circuits controlling the operation of said electrically operated steam controlling means to various stages of its open and shut positions, means for the energization of said relays to move said electrically operated steam controlling means through the various stages of operation, comprising an auxiliary water tank connected with the boiler to maintain a water level variable in accordance with the water level in said boiler, a contact with a source of electrical current supply positioned in said water, and a series of contacts connected to said relays for the operation thereof and positioned at differ-

ent levels in said auxiliary tank for energization and de-energization upon contact with the water in said tank, shield members positioned around said contacts for preventing energization thereof due to splashing of the water, and said shields being adapted to permit energization of said contacts when positioned below the water level.
